UNITED STATES PATENT OFFICE.

BRIDGET BING, OF NEW YORK, N. Y.

DESIGN FOR A QUILT OR SIMILAR ARTICLE.

Application filed March 15, 1929. Serial No. 30,484. Term of patent 7 years.

To all whom it may concern:

Be it known that I, BRIDGET BING, a citizen of the United States, residing at New York, in the county of New York and State of New York, have invented a new, original, and ornamental Design for a Quilt, or similar article, of which the following is a specification, reference being had to the accompanying drawing, forming part thereof.

The figure is a face view of a quilt, or similar article, showing my new design.

I claim:

The ornamental design for a quilt, or similar article, as shown.

In testimony whereof I have affixed my signature.

BRIDGET BING.
